BONNET LID FASTENING DEVICE

Lucien Peras, Billancourt, France, assignor to Regie Nationale des Usines Renault, Billancourt, France

Filed Nov. 16, 1962, Ser. No. 238,159

Claims priority, application France, Nov. 21, 1961,

879,628, Patent 1,313,913

1 Claim. (Cl. 292—216)

This invention relates to fastening devices such as 10 catches or locks of luggage compartment lids and more particularly of automobile bonnet lids, and provides a safety fastening device for automobile lids or bonnets which is characterized inter alia by the following advantages:

- (1) Flexible cable opening control system;
- (2) Automatic fastening by allowing the lid to drop, or by pushing same;
- (3) The provision of a safety catch giving a half closed or incomplete position;
- (4) During the lid opening movement, the lid is slightly shifted outside its frame so that it can be seized with the hand after actuating the lock and subsequent to the positive ejection effect due to the spring;
- (5) The weatherstrips are compressed toward the end of the closing movement by the (negative) spring effect.

According to the present invention, the bonnet lid lock or catch consists mainly of two separate members interconnected by a control pin, i.e.:

- (a) The control and safety device;
- (b) The movable closing keeper and the bonnet centering device.

This invention is characterized essentially in that it comprises a fastening device wherein a cross member of the vehicle body supports the control and lock members as well as the movable-keeper closing device engaging the bolt carried by bonnet lid, these control and lock members and the keeper being separated and operatively interconnected by means of a pin whereby the operator, by acting on the control member and with a single movement will release firstly the lock members and then the keeper 15 from the bolt.

With the foregoing and other objects in view, the invention resides in the novel arrangement and combination of parts and in the details of construction herein-after described and claimed, it being understood that changes in the precise embodiment of the invention herein disclosed may be made within the scope of what is claimed without departing from the spirit of the invention.

Other objects and advantages will become apparent from the following description taken in conjunction with the accompanying drawings in which:

FIGURE 1 is a section taken through the front portion of the body of an automobile and the rear portion of a hingedly mounted bonnet along a plane at right angles to the lock-supporting body cross member on the side of the bonnet lid lock members;

FIGURES 2, 3 and 4 show respectively the lock members in the bonnet closing, half-closing and opening positions;

FIGURE 5 is a section similar to FIG. 1 but taken from the side of the lock bolt and keeper, the keeper being in locking engagement with the bolt;

FIGURE 6 shows the same members as FIG. 5 but with the keeper released from the bolt;

FIGURE 7 is a fragmentary section taken upon the line VII—VII of FIG. 5; and

FIGURE 8 is a plan view from above showing the cross member of the vehicle body which supports the lock members as well as the keeper, the bonnet being removed.

2

Referring firstly to FIG. 1 the reference numerals 1 and 2 designate respectively the vehicle bonnet and an internal cross-member for reinforcing the bonnet; the body 3 comprises a marginal portion or frame 4 defining the bonnet aperture and carrying a weatherstrip 5. The fixed cross member 6 supporting the lock is secured on the one hand on the dashboard 7 and on the other hand on the partition 8 defining the space 9 in which the different component elements of the heating, defrosting and ventilating system of the vehicle are housed. Secured by bolts 13 on this cross member are a pair of brackets 10, 11 carrying bearings for rotatably mounting the control pin 14. This pin 14 has one end rigid with the movable keeper 15 and the other end solid with the lock member 16. This lock member 16 is constantly urged for rotation in the direction of arrow 17 by the inherent elasticity of the weatherstrips, but nevertheless it is held in its closed position by a super-abundantly antagonistic traction spring 18 so that 20 the arrangement provides a negative effect; the lock member 16 is formed with a pair of notches 21, 22 and has a link 23 pivoted at 24 on its upper portion. Formed in the opposite end of this link 23 is an elongated aperture 25 engaged by a pin 26 solid with the lock control cable 27 and also with the lock arm 28. The latter is rotatably mounted on a fixed pin 29 and urged in the direction of arrow 31 by a spiral spring 30; moreover, this lock arm 28 comprises a tooth 32 adapted to co-act with the notches 21 and 22 of the keeper member, in 30 a manner to be set forth presently.

The free end of cable 27 is attached to a control handle 33 by being wound in a central groove 34 thereof and retained by a crimped anchor member 35. Along 35 its path and notably through the dashboard the cable may be guided in flexible pipes or sheaths 36 permitting the necessary changes in direction while sealing the passages through the dashboard or like partitions.

This arrangement is completed by a bolt 37 secured on the cross member 2 by means of a strap 38, and also by a cylindrical boss 39 rigid or formed integrally with the bracket 11 for the purpose of constantly centering the bonnet during its closing movement by engaging a complementary recess of strap 38.

This bonnet lock operates as follows:

In the closed position of the bonnet as illustrated in FIGS. 1 and 5, the tooth 32 of lock arm 28 engages the notch 22 of lock member 16 (FIG. 1) rigid with pin 14 carrying the keeper 15 in locking engagement with bolt 37 (FIG. 5).

To open the bonnet lid the control handle 33 is pulled home to rock the link 23 downwards and thus carry along both the lock arm 28 (in the release direction opposite to arrow 31, FIG. 1) and the lock member 16 (in the direction of arrow 17). The member 16 is urged in the opening direction by the coil tension spring 18 immediately after clearing the position in which said spring is aligned with pin 14. The member 16, link 23 and arm 28 are in the respective positions illustrated in FIG. 2, and the bolt 37 is lifted by the movable keeper 15 carried along by the pin 14 rigid with member 16 (FIG. 6).

Upon releasing the handle 33, the lock arm 28 urged by spring 30 in the direction of arrow 31 moves to the position shown in FIG. 4 and during this movement carries along the link 23 and arm 28, thus giving the open-bonnet position of the parts.

To close the bonnet lid the latter is either simply allowed to drop or depressed manually; thus, the bolt 37 pushes the keeper 15 which, through the medium of pin 14, carries along the lock member 16 in the direction of 70 posite to the arrow 17. This movement of rotation of member 16 permits the locking engagement of lock arm

28 (urged by spring 30) either with notch 21 if an incomplete closing position is desired, or with notch 22 if the lid is to be closed completely (FIG. 1).

Although the present invention has been described in conjunction with a preferred embodiment, it is to be understood that modifications and variations may be resorted to without departing from the spirit and scope of the invention, as those skilled in the art will readily understand. Such modifications and variations are considered to be within the purview and scope of the invention and appended claim.

I claim:

Device for fastening the bonnet lid of a vehicle, characterized in that a cross member of the vehicle body supports control and lock members as well as a locking device proper comprising a movable keeper engaging a bonnet-carried bolt, said control and lock members and said keeper being separated and operatively interconnected by a pin, whereby a single actuation of the control member is sufficient for firstly releasing the lock members and subsequently the keeper from the bolt, and wherein two brackets carried by said cross member

of the vehicle body are provided with bearings for receiving the connecting pin rigid on the one hand with the movable keeper and on the other hand with the lock member proper urged by a spring and provided with two notches, one for locking the bonnet lid in the closed position and another for keeping the bonnet lid in a half-closed position, said lock member co-acting with a tooth formed on a lock arm pivoted on a fixed pin and urged by a spring, said lock arm carrying another pin slidably engaging an elongated aperture formed in a link pivoted on said lock member and so connected to a traction control cable that when said cable is pulled the pin of said lock arm moves to one end of said elongated aperture and carries along the lock member while releasing the tooth of said lock arm and rotating said keeper, whereby said keeper lifts the bolt and the bonnet lid.
